UNITED STATES PATENT OFFICE.

WILLIAM L. SHEPHERD, OF DANVILLE, IOWA.

TRACTION-ENGINE.

SPECIFICATION forming part of Letters Patent No. 299,427, dated May 27, 1884.

Application filed March 15, 1884. (No model.)

To all whom it may concern:

Be it known that I, WILLIAM L. SHEPHERD, a citizen of the United States of America, residing at Danville, in the county of Des Moines and State of Iowa, have invented certain new and useful Improvements in Springs for Traction-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to certain new and useful improvements in spring-supports for traction-engines, its object being to provide a spring-bearing for the wheels which support the boiler, whereby a vertical movement of 20 the same will be allowed without interfering or slackening the propelling means.

25 In the drawings which illustrate my invention, Figure 1 is a side view showing my invention applied to a traction-engine. Fig. 2 is a detail perspective view. Fig. 3 is a sectional view, and Fig. 4 a detail view, of the sliding block.

30 A represents a traction or portable engine, which is mounted on wheels, and is provided with means for propelling the same, which means consist of chains or belts which pass from the engine to a pulley attached to the same, at a suitable point from which pulley another belt passes over a flange or pulley attached to the driving-wheel, which is indicated by the letter B.

35 C represents a curved and slotted case, which is firmly secured by rivets or bolts to the engine. This case is curved, so as to form the segment of a circle, the center of the pulley c forming the center of the arc. The lower end of the case may be open, so that the block

D, which is shaped so as to correspond with the T-slot, may be inserted therein; or the lower end may be closed, in which case the block will be inserted before the same is attached to the boiler. Upon the sliding block D is firmly secured a stub-axle, e, which passes through the hub of the wheel B. Before the block D is inserted in the slotted plate a suitable spring, F, is placed in the opening, so as to form a spring-bearing for the block D. The upper end of the spring, bearing upon the closed end of the case C, and being of a greater diameter than the slot, will be prevented from falling out of said opening. When a spiral spring is employed, the upper end of the same may be secured to the closed end of the case, while its opposite end is attached to the sliding block, which will prevent the block falling out of the slot when the wheel is removed for lubricating. The sliding block D has side flanges, d, d, and a raised central portion, d', to which the stub-axle e is attached, and the slot in the plate corresponds in shape therewith, both being curved, as shown.

40 It will be evident from the foregoing description of my invention that I provide a spring-bearing for the axle, and that a change of position of said axle will not loosen the driving-belt as the different pulleys will always be at the same distance from each other.

What I claim is—

45 In a traction-engine, the curved slotted case C, attached thereto and provided with a spring, and a sliding block, D, having a stub-axle, substantially as shown, and for the purpose set forth.

In testimony whereof I affix my signature in presence of two witnesses.

WILLIAM L. SHEPHERD.
